UNITED STATES PATENT OFFICE.

GEORGE WASHINGTON PALMER, OF NEW YORK, N. Y.

DESIGN FOR A HANGER FOR WASHING-MACHINES.

SPECIFICATION forming part of Design No. 30,576, dated April 18, 1899.

Application filed March 4, 1899. Serial No. 707,806. Term of patent 3 $\frac{1}{2}$ years.

To all whom it may concern:

Be it known that I, GEORGE WASHINGTON PALMER, a citizen of the United States, and a resident of New York, (Brooklyn,) county of 5 Kings, and State of New York, have invented and produced a new and original Design for Hangers for Washing-Machines, of which the following is a specification, reference being had to the accompanying drawing, forming a 10 part thereof, in which similar letters of reference indicate corresponding parts.

The figure is a perspective view of a hanger for washing-machines, showing my new design.

15 As shown in the drawing, the leading or material feature of my design consists of a flat body *a*, having an angular extension *b* at its end, said body being provided with parallel longitudinal slots or openings *c c*, and 20 the angular extension being projected upwardly from one edge of the body and extending transversely across the latter, as at *b*, and then continued outwardly and on a plane above and approximately parallel to the body, 25 as at *c*. The body *a* is shown with a recess *f*, extending longitudinally from the rear edge toward the front edge centrally of the body

and intermediately between the slots or openings *c*, and the rear edges of the said recess *f* are beveled, as at *g*.

30 The device constituting my new design for a hanger for washing-machines has the outer portion of the angular end extension *b* projected downwardly from the top part *c* and extending in parallel relation to the part *d*, 35 as shown at *h*.

The various surfaces of the body and angular end extensions are flat or smooth, as shown.

Having thus described my invention, what 40 I claim as new, and desire to secure by Letters Patent, is—

The design for a hanger for washing-machines, substantially as herein shown and described.

45 In testimony that I claim the foregoing as my invention I have signed my name, in presence of two witnesses, this 3d day of March, 1899.

GEORGE WASHINGTON PALMER.

Witnesses:

JOHN GRAHAM,
CHARLES HENRY PALMER.
